UNITED STATES PATENT OFFICE.

ANDREW J. WEIS, OF DAYTON, OHIO.

BEATING MACHINE FOR PAPER-PULP.

1,301,629.

Specification of Letters Patent. Patented Apr. 22, 1919.

Application filed November 12, 1917. Serial No. 201,440.

To all whom it may concern:

Be it known that I, ANDREW J. WEIS, a citizen of the United States, residing at Dayton, in the county of Montgomery and State 5 of Ohio, have invented certain new and useful Improvements in Beating-Machines for Paper-Pulp, of which the following is a specification, reference being had therein to the accompanying drawing.

10 This invention relates to beating machines for paper pulp, and discloses a machine of the Hollander type. Such machines have been employed for many years and they comprise a roll provided with a number of knives 15 or bars, this beating roll being positioned over a bed-plate, which has parallel bars, generally placed at an angle to the axis of the beater roll. The roll rotates over the bed-plate, so that the knives in the roll may pass 20 over the bars of the bed-plate whereby to disintegrate the fibers of the material operated on.

The knives or bars in the beater roll (sometimes called fly-bars) are subjected to considerable pressure and, therefore, wear gradually and so must be replaced or adjusted. In some machines of the prior art the knives have been so held on the roll as to make their 25 detachment therefrom very difficult. One method of fastening the knives to the roll has been to form slits in the ends of the knives, these knives being carried between radial ribs on the beating roll. A metal band was then heated and shrunk on the roll, it 30 passing through the slits in the knives. While this made a rigid fastening, it was very troublesome to withdraw the shrunk band, but such an operation was necessary each time a single knife needed adjustment 35 or replacement.

The present invention aims to improve the method of fastening the knives or bars on the beater roll, by providing clamping devices associated with one or two knives only and 40 adapted to hold the knives rigidly in their proper position on the roll. Thus to replace a knife it is necessary only to release the clamp for the particular knife, whereupon the knife may be readily readjusted or re-50 placed. The tightening of the clamp again holds the knife fast to the roll. No release or displacement of the other knives is caused.

In the preferred form shown in the drawings, the clamp is of a wedge form and serves 55 to force the knives positively to engagement with the radial ribs of the beater roll. Thus

it not only holds the knives in proper position, but also forces them positively to that proper position.

In the drawings, Figures 1 to 3 show the preferred form, Fig. 1 being an end elevation of a beater roll and its bed-plate; Fig. 2, a fragmentary vertical longitudinal section of one end of the roll; and Fig. 3, a vertical detail in section of part of the end of the roll. Figs. 4 and 5 are fragmentary details in vertical section showing different modified forms of clamping devices.

The drawings show three methods and the preferred form shown in Figs. 1 to 3 will be first described. The ordinary beater roll 1 employed in the art is used in this invention. It will be understood that the roll forms generally a cylinder in its shape, being composed of two end plates or wheels, and in some cases having a central stiffening plate. The entire roll is not shown in the drawings, as it is well known in the art. The ends of the roll comprise central portions 2 and peripheral rings 3, the rings and central portions 40 being connected by a depressed flange 4. The three portions of the wheel, namely, the central portion 2, the flange 4 and the ring 3, are shown as being integral and they may be cast as a unit. Also integral with the 45 wheel are ribs 5 projecting radially from the ring portion 3 and spaced apart, as shown in Fig. 1. Between each two adjacent ribs 5 are mounted a pair of knives or bars 6, these being sometimes termed fly-bars in the art. 50 It will be understood that while these elements 6 are referred to in the specification and claims as knives, nevertheless generally they are not brought to a sharp operating edge. The action is more a scraping action 55 than a cutting action, and the operative edges are left somewhat blunt, as shown in all the figures. As shown in Fig. 3 the pairs of knives 6 between any two adjacent ribs 5 are held to place and pressed against these ribs 100 by a wedge 7. Fastened to this wedge is a screw 8 (Fig. 2) having threads which are engaged by a nut 9. As indicated in Fig. 2 the ring portion 3 of the wheel is pierced to permit the passage therethrough of the screw 105 8 and the nut 9 is inside the ring portion, room to turn the nut being provided by the position of the depressed flange 4.

Fig. 1 shows the bed 10 and the bed-plates 11 used in the beating machine, but these 110 need not be described particularly. The plates 11 may be arranged at an angle to the

shaft 12 of the beater roll, if desired, and that is frequently done in the art. To prevent the liquid from entering the cutout portion surrounded by the depressed flange 4 and the peripheral ring 3, a plate 13 may be employed, held against the side of the roll in any desired manner.

It will be seen that each pair of knives 6 is held and clamped in position by an independent wedge 7 and the operation of inserting the knives consists merely in placing them between the ribs 5 and in then tightening the wedge 7 between them by means of the screw 8 and the nut 9. The radial movement of the wedge, of course, forces the knives 6 tightly against the ribs 5, and it will be observed that the edges of the ribs are nearly radial from the center of shaft 12 of the beater roll. The knives 6 rest directly 20 on the peripheral ring between the ribs 5 and so are held rigidly in proper and exact position.

In order to replace or readjust one of the knives 6, the corresponding wedge 7 is released by operation of the nut 9, whereupon the knife may be withdrawn so as to permit the insertion of another or it may be sharpened and then replaced.

It will be observed that this construction 30 well accomplishes the object first stated, in that it provides for readily detaching and then replacing or readjusting any of the knives, and in any case only two knives are released by the operation of any one wedge 35 7. This is obviously much simpler and quicker to accomplish than to release a shrunk band holding all the knives on the beater roll, and then to perform whatever operation of replacing a knife is necessary.

40 It will, of course, be understood that as usual in the art the beater roll is provided with a similar wheel 2 at its other end, having similar wedges 7 and the other parts, the knives 6 extending across to the other end of the roll and being there clamped in a similar manner. Ordinarily a block of wood fitting between each pair of knives 6 is employed, this block of wood extending substantially from one end of the roll to the 45 other. Such blocks of wood being common in the art and no part of this invention, are not shown.

In the modified form of Fig. 4 the same general construction of wheel is employed, 55 having a circular central portion 2^a and depressed flange 4^a and a peripheral ring 3^a. In this case the ribs 5^a are spaced apart a distance which permits insertion of only one knife 6^a between each two adjacent ribs. A 60 clamp 8^a is provided, passing through a hole in the peripheral ring 3^a, and a nut 9^a serves to tighten the clamp, which, in this case, passes into a notch 14 in the knife 6^a. In this construction each knife is provided with 65 a separate clamp and, therefore, it is neces-

sary to release only one knife in order to make adjustments thereof. The operation is obvious from the description and drawing and consists merely in tightening the nut 9^a, thereby moving the clamp 8^a toward the 70 center 12 of the beater roll and thus forcing the knife 6^a to proper position against the peripheral ring 3^a and to the bottom of the notch or cut between each two adjacent ribs 5^a. 75

In the form shown in Fig. 5, the peripheral ring 3^b is provided with ribs 5^b, and like the form of Fig. 4, these are spaced apart to permit the insertion of one knife 6^b only. The clamp 8^b passes through notches 80 14^b in two adjacent knives and is tightened in the same manner as in the other forms. Thus in the form of Fig. 5 release of two adjacent knives 6^b is required to adjust either one of the two, but the remaining 85 knives of the beater roll remain in attached condition and are not disturbed.

It will be seen that in all three of the forms there is provided the peripheral ring and the depressed flange, thus permitting a 90 screw or bolt to pass through the peripheral ring and allowing room to tighten the nut in front of the depressed flange. Operation of the screws in each case serves to draw the knives radially of the wheel until they rest 95 on the bottom of the notches between the ribs of the peripheral ring. In the form of Figs. 1 to 3 there is the additional advantage that the knives are not required to fit closely the spaces between the ribs, but the 100 wedge 7 provides means for forcing these knives directly against the sides of the ribs and thus less exactness in the construction of the ribs and the spaces between them is required. 105

Fig. 3 shows a form of fastening for the wedges 7 alternative to the form of Fig. 2. In Fig. 3, a bolt 8^c passes through each wedge 7, the bolt ending in an elongated rounded head 8^d, which is held in the enlarged end of a hole 7^c passing through the wedge 7. The operation of this bolt 8^c is the same as that of the screw 8. 110

It will be observed that the form of knife in Figs. 1 to 3 differs slightly from the form of Figs. 4 and 5. In the preferred form the sides of the knives are straight and inclined to each other, thus making the knives symmetrical. Therefore, the knives are usable on either "right handed" or "left 120 handed" rolls, and thus are an improvement on the forms of knife of Figs. 4 and 5 which can only be used to face in one way on the roll.

Having thus fully described my invention, what I claim as new, and desire to secure by Letters Patent, is:—

1. In a pulp beater, the combination, with a wheel having a central portion, and a peripheral ring portion connected with the 130

central portion by a depressed flange, of radially projecting ribs integral of said ring portion spaced apart to form a substantially rectangular shaped space therebetween, two 5 knives between each two adjacent ribs, a wedge between said two knives and pressing said knives against said ribs, and means passing through the peripheral ring and operable to force said wedge toward said 10 ring.

2. In a pulp beater, the combination, with a wheel, having a central circular portion, and a peripheral ring portion, connected with the central portion by a depressed 15 flange, of radial ribs integral of said ring portion, the outer surfaces of said ribs being nearly radial from the center of said wheel, the faces of said ribs opposite each other being substantially parallel to a radial plane therebetween, two knives between each two adjacent ribs, a wedge between 20 said knives and constructed to force said knives against said ribs, a screw fast to said

wedge and passing through said ring portion and in front of said depressed flange, 25 with means for drawing said screw toward the center of said wheel, thereby forcing the wedge to operative position.

3. In a pulp beater, the combination, with a wheel cast to form a circular central portion, a depressed flange extending radially, and a peripheral ring portion, extending axially, said central portion, said depressed flange and said ring portion being integral with each other, of radially extending ribs 30 cast integrally of said ring portion and having substantially rectangular shaped spaces therebetween, knives between said ribs projecting radially and resting on the outside of said ring portion, wedges for said knives 35 for holding them tightly against said ring portion, and means passing through said ring portion for forcing said wedges toward the center of said wheel.

In testimony whereof, I affix my signature. 40
ANDREW J. WEIS.
